Wm. Van Anden,
Mower.

No. 44.477

Patented. Sep. 27. 1864.

UNITED STATES PATENT OFFICE.

WILLIAM VAN ANDEN, OF POUGHKEEPSIE, NEW YORK.

IMPROVEMENT IN MOWING-MACHINES.

Specification forming part of Letters Patent No. 44,477, dated September 27, 1864.

To all whom it may concern:

Be it known that I, WILLIAM VAN ANDEN, of Poughkeepsie, Dutchess county, State of New York, have invented certain new and useful Improvements in Mowing-Machines; and I do hereby declare the following to be a full description of the same.

The nature of my improvements consists, first, in suspending the cutter-bar frame upon a journal or bearing having one end supported by a hanger from the front end of the frame of the machine and the other to the outer end of the axle-tree of the propelling-wheels of the mower, and thereby give greater steadiness to the motion of the cutter-bar, and at the same time allow it to have a free up-and-down motion to adapt itself to the inequalities of the ground; and, second, in the method of tipping or elevating the outer point of the cutter-bar by means of a hand-lever operating a toe-piece (secured to the frame of the machine) against a cam attached to the side of the cutter-bar frame.

To describe my invention more particularly, I will refer to the accompanying drawings, forming a part of this specification, the same letters of reference, whenever they occur, referring to like parts.

Figure 1 is a plan view of the machine. Fig. 2 is a side view of the machine. Fig. 3 is a side view of the machine through the line *x x*, Fig. 1. Fig. 4 is a front view of the machine, showing the application of lever and toe-piece in elevating the outer end of the cutter-bar. Fig. 5 is a detached sectional view of the hand-lever and toe-piece as secured to the frame of the machine. Fig. 6 is a detached plan view of the toe-piece and hand-lever. Fig. 7 is a detached sectional view of the front end of the cutter-bar frame and cam attached thereto and toe-piece.

Letter A is the frame of the mower, which is secured upon the axle-tree B of the propelling-wheels C by suitable boxes, D, bolted to the under side of the side rails of the frame. On this frame will be arranged the multiplying gear-wheels for propelling the cutter, and on the sides of the propelling-wheels of the mower suitable gear-wheels for communicating motion to the multiplying gear-wheels; but as these parts form no part of my invention they have been omitted (in the model) as immaterial in exhibiting the improvements I desire to have

patented. It will be apparent, however, that from the attachment of the frame to axle-tree it is not designed to have it revolve with the propelling-wheels C; but, on the contrary, it is designed to be in effect like the axle-tree of a wagon, having spindles formed on its ends upon which the wheels revolve, like wagon-wheels, independent of each other, and are alternately thrown in and out of gear with the cutter-bar gear-wheels by suitable coupling-boxes for that purpose under control of the attendant of the machine.

The object of making the axle-tree fixed or non-revolving will be obvious as necessary for making a bearing or place of fixed support for one end of the cutter-bar-journal frame E. By this means the journal is shortened in length one-half what it would be if extended so as to have a bearing on the frame of the machine, and just in proportion as it is shortened is it increased in stiffness and ability to resist the jarring concussions of the cutter at each vibration, and at the same time cheapens the cost of making it.

Letter F is the cutter-bar frame, secured upon the journal E; and G is a hanger, attached to the frame A, for supporting the lower end of the journal.

Letter H is a tapis or cam-like projection formed on the inner edge of the cutter-bar frame just below the bearings of the journal E, and which is operated upon by the toe-piece I of a lever, J, secured by a center pin, K, to the under side of the frame of the mower. This toe-piece has a beveling face. The object of this is to cause a gradually-increasing leverage or bearing against the face of the cam H as it rotates around the journal E, and at the same time to adapt it to the longitudinal vibratory motion in consequence of its position on the frame of the mower.

Letter L is a hand-lever, attached by a center-pin, M, to the frame of the mower just back of the front rail, so that its lower end may act upon the back end of the lever J, and to which it is connected by a link, N, so as to draw it in to relieve the toe from off the cam, and thus let the cutter-bar down upon the surface of the ground again.

Letter P is an inclined plane, secured to the side of the tongue or pole R of the mower, and upon which the lever L operates to lift the cutter-bar by means of the pin S in the side of it.

The operation of these parts is that when the hand-lever is projected over the front rail link of the mower, as in Fig. 1, and the pole attached to the horses, the frame and cutter-bar rises and falls with the inequalities of the ground over which it passes without interference from the lever; but when it is desirable to elevate the cutter-bar from off the ground it is then only brought into action by the attendant drawing toward him the upper end of the hand-lever, and thus lifting the frame of the mower in consequence of the pin S drawing back upon the inclined guideway, and at the same time tipping or elevating the outer end of the cutter-bar by means of the toe-piece I acting upon the cam H.

Having now described my improvements, I will proceed to set forth what I claim and desire to secure by Letters Patent of the United States:

1. The short inclined journal E, united at its upper end directly to the axle B and affixed at its lower end by a hanger, G, to the frame A, in the manner and for the purpose described.
2. The arrangement of the stationary axle B, short inclined journal E, and vibrating cutter-bar frame or shoe F, constructed and oper-

erating in the manner and for the purpose described.

3. The combination of the link N, lever-cam I J, and cam H with the vibrating cutter-bar frame or shoe F, substantially in the manner and for the purpose described.

4. The combination of the lever L, link N, lever-cam I J, cam H, vibrating cutter-bar frame or shoe F, and journal E, substantially in the manner and for the purpose described.

5. The arrangement of the cam H and the horizontally-swinging cam-lever I J with the vibrating frame or shoe F and the journal E, substantially in the manner and for the purpose described.

6. The combination of the inclined plane P, when attached to the pole of a mowing-machine, with the hand-lever L and vibrating lever J, for the twofold purpose of lifting the front of the mower-frame and at the same time tipping the outer end of the cutter-bar, as hereinbefore set forth.

WM. VAN ANDEN.
